FOUNTAIN PEN

Paul Stranszky, Vienna, Austria, assignor to
W. A. Katzenstein, Jackson Heights, N. Y.

Application December 10, 1937, Serial No. 179,183
In Austria April 21, 1937

3 Claims. (Cl. 120—49)

My invention relates to fountain pens, and more particularly to a fountain pen for use by one hand, in which a cap housing is slidably and undetachably mounted on the end of the barrel carrying the nib.

In the hitherto known fountain pens of above described type, the cap housing is provided with a flap hinged thereto. When the cap housing is in the position enclosing the rib, the flap is closed, and when the cap housing has to be shifted into the position liberating the nib for use, the flap is opened. It has been found, however, that a perfect tightening between the flap and the cap housing is impossible, so that a drying up of the nib occurs which prevents an immediate writing when the fountain pen is used again.

One object of my invention is to provide a fountain pen of above described type, which is instantly ready for use when the cap housing is shifted into the position liberating the nib.

Another object of my invention is to provide a fountain pen of above described type, which is perfectly sealed when the cap housing is in the position enclosing the nib.

A further object of my invention is to provide a fountain pen of above described type, which has a simple construction and may be easily manipulated.

In order to carry out my invention into practice I provide a fountain pen comprising a barrel, a nib mounted on said barrel, a housing slidably and undetachably mounted on said end of the barrel, said housing having an opening for the passage of the nib, said housing enclosing said nib in its normal end position, said housing liberating said nib in its other end position for use of the fountain pen, an ink feeding device in said barrel, and actuating means for actuating said ink feeding device to force ink into the nib for priming same and to suck back a remainder of ink from the nib into the ink feeding device, said actuating means being arranged on said barrel in the path of said housing, said housing being adapted to operate said actuating means for priming the nib when the housing is shifted into the position liberating the nib, and said housing being adapted to operate said actuating means for sucking back the remainder of ink when the housing is shifted into the position enclosing the nib.

The above mentioned objects and advantages as well as other objects and advantages will be more fully disclosed in the following specification reference being had to the accompanying

drawing forming part of this specification, in which:

Fig. 1 is a side elevational view of a fountain pen with the cap housing in the position enclosing the nib, 5

Fig. 2 is a side elevational view of the fountain pen with the cap housing in the position liberating the nib, 10

Fig. 3 is a top plan view of the fountain pen shown in Fig. 1, 10

Fig. 4 is a sectional view of the fountain pen taken on line 4—4 of Fig. 1, and 10

Fig. 5 is a fragmentary sectional view of a different embodiment of the fountain pen.

Referring now to Figs. 1—4, 1 indicates the barrel of the fountain pen. The nib holder 2 carrying the nib 4 is secured to the barrel 1 in any suitable manner. A collapsible ink sack 5 arranged in said barrel 1 communicates with the nib 4 through a channel 3 in the nib holder 2. 15

A blade spring 6 adapted to cooperate with the ink sack 5 is also arranged in the barrel 1. Said spring 6 carries a button 9 or the like extending through an opening 10 of the wall of the barrel and projecting from the outside of the barrel. The lower end of the spring 6 abuts against a filling pin 7 movably arranged in a bore of a bushing 20 mounted in the lower end of the barrel 1. A cap 8 enclosing the pin 7 is screwed onto the end of the barrel 1. 20

A cap housing 14 is slidably and undetachably mounted at the upper end of the barrel 1 by means of a pin and groove connection 21, 22 or the like. The housing 14 has a slot 16, and said slot 16 is in engagement with the button 9 carried by the spring 6, when the housing 14 is in its normal end position enclosing the nib 4. Furthermore, the housing has an opening 15 at its top for the passage of the nib 4, when the housing is shifted into its other end position liberating the nib for use of the fountain pen as shown 25 in Fig. 2. 30

The operation of the fountain pen is as follows: When it is desired to make the fountain pen ready for use, the cap housing 14 is moved from its normal end position shown in Fig. 1 35 into its other end position shown in Fig. 2. During the first portion of this movement the slot 16 slides along the button 9 and the latter and the spring 6 remain in the position shown in full lines in Fig. 4. During the second portion of this movement, however, the button 9 projecting from the outside of the barrel 1 comes into the path of the body of the housing 14, as soon as 40 the edge 23 of the slot 16 comes in contact with 45

50

55

the button 9. When the shifting of the housing 14 is continued after the contact between the edge 23 and the button 9, the button 9 is pressed inwardly by the wall of the housing 14, so that the spring 6 is brought into the position 6' shown in dash lines in Fig. 4. Thus, the button 9 and spring 6 actuate the ink sack 5 to force ink into the nib 4 through the channel 3 for priming the nib liberated by the housing 14, so that the fountain pen is immediately ready for use. During the use of the fountain pen, the ink is fed from the ink-sack 5 to the nib 4 through the channel 3 in usual manner.

When, after the use of the fountain pen, the housing 14 is moved from the position shown in Fig. 2 into the position shown in Fig. 1, the spring 6 carrying the button 9 returns into the position shown in full lines in Fig. 4, as soon as the edge 23 is disengaged from the button 9. During this return movement of the actuating means 6, 9 the remainder of the ink is sucked back from the nib into the elastic ink feeding device 5, and this sucking back of the remainder of the ink is sufficient for a drying up of the nib to such a degree, that no ink may pass through the capillary ink channel 3 to the nib when the housing 14 is in the position enclosing the nib as shown in Figs. 1 and 4.

It will be readily understood that the shifting 30 of the housing 14 from the position shown in Fig. 1 into the position shown in Fig. 2 and vice versa may be easily carried out by one hand.

When it is desired to refill the ink-sack 5, the housing 14 is shifted into the position shown in Fig. 2 and the cap 8 is unscrewed from the barrel 1. The nib 4 is inserted into the ink in a bottle, and the filling pin 7 cooperating with the spring 6 is pressed and released several times, whereby the ink is sucked into the ink-sack 5.

Fig. 5 illustrates a different embodiment of a fountain pen. The barrel 1 does not contain a special ink-sack for the ink supply. The ink is filled directly into the ink supply chamber 24 of the barrel 1 by means of a piston 11 in a manner known per se. The barrel 1 has a recess receiving an elastic sleeve 13 of rubber or the like. The button 9 is connected to this sleeve 13. When the housing 14 is moved into the position liberating the nib 4, the button 9 is pressed inwardly by the housing, as soon as the edge 23 comes into contact with the button 9, so that the wall of the sleeve 13 is depressed for priming the nib as shown in dash lines. On the other hand, when the housing 14 is moved from the position liberating the nib into the position enclosing the nib, the button 9 is returned into its projecting position by the elasticity of the sleeve 13 as soon as the button is disengaged from the edge 23, and the remainder of the ink is sucked back from the nib 4 into the ink supply chamber 24 by means of the sleeve 13 resuming its normal expanded shape.

I have described preferred embodiments of my invention, but it is clear that numerous changes and omissions may be made without departing from the spirit of my invention.

What I claim is:

1. A fountain pen comprising a barrel, a nib mounted on said barrel, a housing slidably and undetachably mounted on said end of the barrel, said housing having an opening for the passage of the nib, said housing enclosing said nib in its normal end position, said housing liberating said nib in its other end position for use of the fountain pen, an ink feeding device in said barrel, and actuating means for actuating said ink feeding device to force ink into the nib for priming same and to suck back a remainder of ink from the nib into the ink feeding device, said actuating means being arranged on said barrel in the path of said housing, said housing being adapted to operate said actuating means for priming the nib when the housing is shifted into the position liberating the nib, and said housing being adapted to operate said actuating means for sucking back the remainder of ink when the housing is shifted into the position enclosing the nib.

2. A fountain pen comprising a barrel, a nib mounted on said barrel, a housing slidably and undetachably mounted on said end of the barrel, said housing having an opening for the passage of the nib, said housing enclosing said nib in its normal end position, said housing liberating said nib in its other end position for use of the fountain pen, an ink-sack lying in said barrel, and a button for actuating said ink-sack to force ink into the nib for priming same and to suck back a remainder of ink from the nib into the ink-sack, said button being movably arranged in an opening of the wall of the barrel and projecting from the outside of the barrel into the path of said housing, said housing being adapted to operate said button for priming the nib when the housing is shifted into the position liberating the nib, and said housing being adapted to operate said button for sucking back the remainder of ink when the housing is shifted into the position enclosing the nib.

3. A fountain pen comprising a barrel, a nib mounted on said barrel, a housing slidably and undetachably mounted on said end of the barrel, said housing having an opening for the passage of the nib, said housing enclosing said nib in its normal end position, said housing liberating said nib in its other end position for use of the fountain pen, an ink supply chamber in said barrel, an elastic sleeve arranged in said ink supply chamber, and a button for actuating said elastic sleeve to force ink into the nib for priming same and to suck back a remainder of ink from the nib into the ink supply chamber, said button being movably arranged in an opening of the wall of the barrel and projecting from the outside of the barrel into the path of said housing, said housing being adapted to operate said button for priming the nib when the housing is shifted into the position liberating the nib, and said housing being adapted to operate said button for sucking back the remainder of ink when the housing is shifted into the position enclosing the nib.

PAUL SZTRANSZKY.
